UNITED STATES PATENT OFFICE.

ALBERT BOUWERS, OF EINDHOVEN, NETHERLANDS, ASSIGNOR TO N. V. PHILIPS' GLOEILAMPENFABRIEKEN, OF EINDHOVEN, NETHERLANDS.

X-RAY TUBE.

Application filed June 9, 1925, Serial No. 35,930, and in the Netherlands July 23, 1924.

This invention relates to X-ray tubes, more particularly to X-ray tubes in which the active portion of the anticathode is made of tungsten. When using X-ray tubes for 5 diagnostic purposes, great energy is as a rule concentrated for a very short time on a small portion of the anticathode, but also in X-ray tubes for therapeutic purposes great energy is frequently supplied to the anticathode. 10 Many means for carrying off this energy have been proposed which may be based on heat conduction or on heat radiation. In spite of these means it occurs, however, that the energy supplied to the anticathode can- 15 not be carried off so quickly that the anticathode is prevented from disintegrating.

An object of the invention is to provide a construction of an X-ray tube in which much energy can be carried off from a very small 20 focal spot. Another object of the invention is to diminish the risk of disintegration of the anticathode. A further object of the invention is to provide an X-ray tube showing a very effective cooling of the active surface 25 of the anticathode.

According to this invention the tungsten anticathode of an X-ray tube of the incandescent cathode type is hollowed at the place of the focal spot. The focal spot in such an 30 X-ray tube being consequently located in a cavity of the anticathode, the cooling is much more effective than in X-ray tubes having a plane anticathode, for in X-ray tubes according to the invention the ratio of the sur- 35 face of the anticathode portion struck by the cathode-rays and the section of the beam of X-rays leaving the anticathode will be greater than it is in X-ray tubes having a plane anticathode. In X-ray tubes having 40 a plane anticathode the surface of which forms an angle of 45° with the direction of the X-ray beam, the ratio of the surface of the focal spot and the section of the leaving beam of X-rays is about $\sqrt{2}$ whereas 45 in X-ray tubes according to the invention comprising an anticathode with a cavity having the form of a cone the solid angle of which is for example 30° , the ratio of the surface of the focal spot and the section of the beam of X-rays leaving the anticathode in the direction of the axis of the cone, will be about 50 4.2. For that reason, too, the cooling of the anticathode at a given sharpness of image

will be more intensive than an X-ray tube in which the active portion of the anticathode 55 forms a plane.

An additional advantage of X-ray tubes according to the invention exists in that in the cavity of the anticathode there is a space nearly free from any electric field. In X-ray 60 tubes as hitherto known it often occurs that the strong field between the cathode and the anticathode draws tungsten particles off the incandescent anticathode, which, on the contrary in X-ray tubes according to the invention owing to the presence of said space nearly free from any electric field, occurs to a 65 less extent so that also on that account the possibility of the anticathode being damaged is diminished.

The invention will be more clearly understood with reference to the accompanying drawing, representing an embodiment of the invention. An incandescent cathode 2 is fixed in a metal vessel 1 to the wall of which 70 is secured a metal cover 3 having an aperture in front of which stretches part of the surface of an anticathode 4. In known arrangements the anticathode of an X-ray tube is provided with a tungsten target mounted 80 in a copper body. The anticathode of the tube illustrated which on the outside may consist for example, of chrome-iron, comprises a tungsten insert 5 surrounded by a mass 6 consisting, for example, of copper, 85 this device differing from incandescent cathode X-ray tubes hitherto known in that the tungsten body 5 has a hollow conical face. In the metal vessel opposite the anticathode is a window for the passage of the X-rays 90 generated. This window consists of a glass hood 7 which is hermetically sealed to the metal wall, an annular metal plate 8, for example, of iron being provided for screening the X-rays and for preventing the weld 9 95 from being struck by cathode rays. One leading-in wire 10 for the incandescent cathode passes insulatingly through the metal ring 8 and is sealed into the glass hood 7; the other leading-in wire is formed by the conductive connection of the pole 11 with the metal ring 8 and the metal envelope 1. The X-ray tube is either highly evacuated or has a gaseous filling of hydrogen or helium having a pressure above 0.0006 millimetre of mercury which is such that any gas ionization 100 105

which should be detrimental to the discharge does not occur. If now during the operation of the X-ray tube the focal spot extends over the area $a-b-c$ of the anticathode, the 5 section of the beam of X-rays emitted will not be larger than the surface $a-c$ so that not only the carrying off of heat is extremely intensive owing to the great surface from which it emanates and especially to the small 10 solid angle of the conical cavity of the anticathode, but also a great sharpness of image can be obtained.

What I claim is:

1. An X-ray tube comprising an incandescent filament cathode and an anticathode con- 15

sisting partly of tungsten, the anticathode being hollowed at the place of the focal spot.

2. An X-ray tube comprising an incandescent filament cathode and an anticathode provided with a hollow cone-shaped insert of tungsten at the place of the focal spot. 20

3. An X-ray tube comprising an incandescent cathode and an anticathode provided with a cone-shaped insert of tungsten of approximately uniform thickness at the place 25 of the focal spot.

In testimony whereof I affix my signature, at the city of Eindhoven, this 20th day of May, A. D. 1925.

ALBERT BOUWERS.
